W. L. Edwin.

UNITED STATES PATENT OFFICE.

EDWARD J. BROOKS, OF EAST ORANGE, NEW JERSEY, ASSIGNEE TO E. J.
BROOKS & CO., OF NEW YORK, N. Y.

SEAL FOR SEAL-LOCKS.

SPECIFICATION forming part of Letters Patent No. 355,636, dated January 4, 1887.

Application filed October 25, 1886. Serial No. 217,124. (No model.)

To all whom it may concern:

Be it known that I, EDWARD J. BROOKS, a citizen of the United States, and a resident of East Orange, in the State of New Jersey, have 5 invented a new and useful Improvement in Seals for Seal-Locks, &c., of which the following is a specification.

This invention relates to that class of seals for "seal-locks" and fastenings of various sorts 10 which are now made of glass, or of glass and paper combined, and in use are inclosed or partly inclosed within a portion of the lock or lock-easing, termed the "seal-holder," in front of a spring-catch or retaining device, so that 15 access to the latter can only be had by breaking the seal.

Heretofore such seals have been unavoidably destroyed as evidence in so breaking them, the entire seal being customarily broken into 20 small fragments and picked out of the seal-holder before the unlocking operation, and it would be impossible to do otherwise as a rule. Consequently, on opening a sealed railway-car, for example, and finding goods missing, there 25 is usually no conclusive evidence that the seal of the class aforesaid which was inspected and broken was a genuine seal applied by the shipper. Moreover, in such seals of glass and paper combined, as heretofore constructed, 30 common window-glass has been almost exclusively used in practice, owing to the expensiveness of those more safe substitutes therefor which have been proposed, thus facilitating the counterfeiting or duplicating of such seals. 35 Not only so, there has been no adequate provision against the entrance of small fragments of the broken seal into the works of the lock.

The present invention consists in certain 40 novel features of construction and combinations and arrangements of parts in seals of said class, or seals adapted to be used in the same or like locks or fastenings, as hereinafter set forth and claimed, whereby conclusive evidence of the character of each seal may be 45 readily preserved, counterfeiting or duplicating is rendered practically impossible by inexpensive means, and the entrance of fragments of the broken seal into the lock is effectively prevented, while at the same time break-

ing the seal in the improved way is facilitated, 50 and accidental breakage can be unmistakably distinguished from violation of the seal.

A sheet of drawings accompanies this specification as part thereof.

Figure 1 of the drawings is a perspective 55 view of a seal embodying all the several features of said invention. Fig. 2 represents a longitudinal section of the same in a seal-holder. Fig. 3 represents a like view of the seal itself, partly broken, illustrating the exclusion of fragments of the seal from the lock. Fig. 4 is a like view illustrating the completion of the breaking operation in the act of unlocking the seal-holder. Figs. 5 to 8, inclusive, represent longitudinal sections of 65 slightly-modified seals. Figs. 9 and 10 are respectively a perspective view and a longitudinal section of another seal, illustrating additional modifications. Figs. 11 to 14, inclusive, represent longitudinal sections of other 70 slightly-modified seals. Fig. 15 represents a cross-section of another modified seal in a seal-holder, and Fig. 16 is a perspective view of the seal last mentioned.

Like letters of reference indicate corresponding parts in the several figures.

Each seal comprises a rigid and frangible cast or molded body, A, which is preferably of transparent glass, provided in the molds or dies with a recess or recesses, r, rendering a 80 portion of the seal very thin, so that it may be readily broken within the area of said portion without breaking it elsewhere, and nearly the whole seal may consequently be preserved intact, as evidence of its character and marks, 85 after it has been so broken to open the lock or fastening which it guards. Said recesses r are so located as to be in line with or opposite the "catch-hole" h in the back of the inner part or "slide," S, of a seal-holder, Fig. 2 or 90 Fig. 15, so that when said thin portion of the seal is broken direct access is had through the break and recess or recesses to the spring-catch C, or other retaining device, by which withdrawal of said slide is prevented, so that 95 the same may be pushed back by a push-key, P, Fig. 4, to unlock the holder. The latter may in turn permit the actuation of a lock, or

may itself, including a suitable housing, H, constitute the fastening of a railway-car door, a safety-case for valuables, or the like. Each seal is, moreover, provided in the molds or dies with permanent distinguishing-marks *m*, which are readily so added, while they cannot be counterfeited or reproduced except in a factory with the aid of like molds or dies and suitable manufacturing plant. It has been found in practice that seal parts which can only be so produced are free from liability to be fraudulently duplicated. Characters *d*, forming the directions "Break here," are likewise preferably formed in the seals by the molds or dies.

In the specific seal represented by Figs. 1 to 4, inclusive, a single recess, *r*, is formed in the back of the frangible body A. The lettering *d* is formed in the bottom of the recess 20 in "cameo" characters, being most readily so formed by "engraving" or die-sinking the end of the matrical projection which forms the recess. The marks *m* ("U. S. Safety Seal," Fig. 1) are formed in *intaglio* characters in the back of the body, and said body is supplemented by a backing, B, of paper or like fabric, cemented to the body A, which is of transparent glass, and bearing in the example, Fig. 1, descriptive printed matter *a*, 30 ("C. to N. Y.") a serial number, *b*, ("9000") and engraving *c*, (lathe-work,) all of which are exposed to view through the transparent body of the seal, as represented in Fig. 1. Said backing B, in connection with said recess *r*, 35 forms a pocket in the seal to receive the fragments of glass when its thin portion is broken, as seen in Fig. 3, so as to prevent their entrance into the lock. If the seal should be so broken accidentally, the fragments would ordinarily remain in the recess, while the backing B would remain intact. Otherwise the fragments are at once blown out, and the push-key P is forced through the backing against the catch C, Fig. 2, as represented in 40 Fig. 4.

The modification represented by Fig. 5 consists in omitting such backing B or employing said body A alone.

In the modified seal represented by Fig. 6 50 the directions *d*, as well as the marks *m*, are *intaglio*, both being formed in the face of the seal-body A.

In the modified seal represented by Fig. 7 55 the directions *d* and marks *m* are both formed by cameo characters on the face of the seal-body A. In that represented by Fig. 8 the marks *m* alone are formed in cameo characters on the face of the seal-body A, the directions *d* being formed within the recess *r*, as in the 60 two seals first described.

The principal modifications represented by Figs. 9 and 10 are a change of shape and a change of location in the recess *r*. It is here shown round and in the face of the seal-body

A, in contrast with the square recess in the back of the seal shown in Figs. 1 to 4. It is obvious that the recess in either location may be of any preferred shape without affecting the before-mentioned functions of the recess, while such shapes may aid in distinguishing 70 seals applied to particular uses. Said seal (represented by Figs. 9 and 10) also illustrates forming said directions *d* and marks *m* by cameo characters on the face of the seal. Its backing B is provided with descriptive matter 75 *a* ("In Bond") and a serial number, *b*, ("N. Y. 7000.")

The modified seal represented by Fig. 11 consists of the seal-body A of the seal last described without its backing B. That represented by Fig. 12 illustrates forming the directions *d* and marks *m* by cameo characters on the back of the seal-body A. That represented by Fig. 13 illustrates forming the directions *d* by cameo characters on the bottom 85 of a face recess, *r*, in connection with *intaglio* marks *m* in the face of the seal-body A. That represented by Fig. 14 illustrates forming the directions *d* by cameo characters on the bottom of a shallow back recess, *r*, in connection 90 with a matching face recess, *r*', and marks *m*', both in *intaglio* and in cameo, and on both back and face of the seal-body A.

The modified seal represented by Figs. 15 and 16 has marginal flanges *f*, by which to 95 hold it in the slide S of the seal-holder S H, so that the entire face of the seal may be exposed, and it is provided on its face with cameo distinguishing-marks *m*, and also with cameo descriptive marks *a*', which may be so prominent as to be distinguished by feeling them. As regards its recesses *r* *r*' and directions *d*, it is like the seal, Fig. 14, just described.

It will be obvious that any of the seals represented by Figs. 6 to 8 and 12 to 16, inclusive, may be provided with suitable backings, B, and that otherwise those having their directions *d* and marks *m* on the face of the seal-body A may be opaque or semi-opaque 105 without loss of function. Other like modifications will suggest themselves to those skilled in the art.

Having thus described my said improvement in seals for seal-locks, &c., I claim as my invention and desire to patent under this specification—

1. A seal having a rigid and frangible body provided with a recess or recesses which render a circumscribed portion of the same very thin, so that this portion may be easily broken through without injuring the remainder of said body, substantially as herein specified, for the purpose set forth.

2. A seal having a rigid and frangible body 125 provided with a recess or recesses which render a circumscribed portion of the same very thin, and having molded distinguishing-marks,

so that the same must be made in molds or dies, substantially as herein specified, for the purpose set forth.

3. A seal having a rigid and frangible body provided with a recess in its back, which renders a circumscribed portion of said body very thin, in combination with a backing of paper or the like, separated from said thin portion

of the body by said recess, so as not to be necessarily broken in the act of breaking through to said thin portion, substantially as herein specified, for the purposes set forth.

EDWARD J. BROOKS.
